UNITED STATES PATENT OFFICE.

ALEX J. JOHNSON, OF NICOLET ISLAND, MINNEAPOLIS, MINNESOTA.

CUTTER-HEAD.

1,268,722.

Specification of Letters Patent. Patented June 4, 1918.

Application filed April 18, 1917. Serial No. 162,875.

To all whom it may concern:

Be it known that I, ALEX J. JOHNSON, a citizen of the United States, residing at Nicolet Island, Minneapolis, in the county of 5 Hennepin and State of Minnesota, have invented certain new and useful Improvements in Cutter-Heads; and I do hereby declare the following to be a full, clear, and exact description of the invention, such as will enable others skilled in the art to which it 10 pertains to make and use the same.

The invention relates to improvements in cutter heads.

It is a well known fact among wood working manufacturers that solid cutter heads 15 are best, especially when working hard and grainy wood and when good work and high speed are desired. This is because the cutting edge is at such an angle that it scrapes 20 rather than cuts; but solid cutters are expensive and are only useful for the one purpose for which they are made, and when used regularly they do not last long and when the cutting edge is worn out the whole 25 head must be discarded.

The object of the present invention is to provide a simple, practical and efficient cutter head of strong, durable and comparatively inexpensive construction adapted to 30 possess all the advantages of a solid cutter head and capable of enabling the cutter to be readily removed and quickly replaced for sharpening purposes and also for enabling various kinds of cutters to be used on one 35 cutter head.

With these and other objects in view, the invention consists in the construction and novel combination of parts hereinafter fully described, illustrated in the accompanying 40 drawing and pointed out in the claims hereto appended; it being understood that various changes in the form, proportion, size and minor details of construction, within the scope of the claims, may be resorted to without departing from the spirit or sacrificing any of the advantages of the invention.

In the drawing:

Figure 1 is a side elevation of a cutter head constructed in accordance with this invention.

Fig. 2 is a transverse sectional view of the "some."

Fig. 3 is a detail perspective view of the cutter.

Like numerals of reference designate cor-

responding parts in all the figures of the drawing.

In the accompanying drawing, in which is illustrated the preferred embodiment of the invention, the cutter head comprises in its 60 construction a solid central body 1 having peripheral faces 2 arranged concentric with a central opening 3 for the reception of the shaft or arbor of a wood working machine. The solid body portion 1, which is relatively 65 thick and which may be constructed of any suitable material, is provided at intervals with peripheral recesses in the cutter supporting faces 2 to provide clearance for the cuttings.

The solid body portion 1 of the cutter head receives a series of cutters 5 having curved inner faces 6 arranged concentric with the body portion of the cutter head and fitting the peripheral faces 2 thereof and secured on the same by means of side plates or sections 7. The cutter supporting body 1 is provided at its side faces with annular recesses 8 which space the outer portions of the side plates 7 from the body 1, and the 80 said outer portions of the side plates 7 are provided with annular grooves 9 having outer walls arranged at an inclination to the axis of the cutter head and adapted to engage similar faces of curved side ribs or 85 portions 10 of the cutters. The side plates are secured to the body portion 1 by transverse bolts 11, which pierce the outer portions of the side plates and the outer portions of the body 1. The bottom or inner 90 walls of the grooves 9 are spaced from the inner faces of the ribs or laterally projecting portions 10 of the cutters to provide intervening spaces 12, which enable the side plates, by being drawn together, to also draw 95 the cutters tightly against the peripheral faces of the body whereby the cutters will be rigidly held in proper position for accurate cutting. The outer face of the cutter is eccentric to provide the necessary 100 clearance and the cutter is provided with a front cutting edge 13. The cutters illustrated in the drawings are designed for use on glue jointers, but the cutter head may be used on shapers, molders and various other 105 wood working machines and may be made of any desired size and with any number of cutters or knives, which will be of the desired configuration to produce the necessary cut. The side plates are provided with cen-

110

tral openings 14 which register with the opening 3 of the body. The central body portion is of the same width as the body portion of the cutters and thereby possesses 5 all the strength required of a solid cutter head and will enable the cutter head to be operated at the desired speed. The knives or cutters, by being arranged upon the solid concentric peripheral portion of the body, 10 will always be in proper position with the cutting edge always at the same radius, provided the cutters or knives are properly dressed and sharpened. The cutter head is adapted to be manufactured as cheaply as a 15 square cutter head and it will do the work of a solid cutter head and will enable the knives or cutters to be rapidly changed when desired.

The side plates are also provided with 20 peripheral recesses conforming to the configuration of the recesses of the central body portion of the cutter head.

What is claimed is:

1. A cutter head of the class described including a solid central body portion provided with peripheral cutter receiving faces arranged concentric with the axis of the cutter head, knives or cutters arranged upon the peripheral faces of the said body and 30 being of substantially uniform width with the same, said knives or cutters having laterally projecting ribs or portions extending beyond the side faces of the said central body portion of the cutter head and provided with outer faces arranged at an angle or inclination to the axis of the cutter head, and 35 annular side plates adjustably secured to the body portion of the cutter head and provided with grooves having inclined outer walls fitting the ribs or projecting portions of the knives or cutters, said grooves being 40

also provided with inner walls spaced from the ribs or projecting portions to enable the side plates to draw the knives or cutters inward radially of the cutter head to clamp 45 the knives or cutters tightly against the body portion of the cutter head.

2. A cutter head of the class described including a solid central body portion provided with peripheral cutter receiving faces 50 arranged concentric with the axis of the cutter head, knives or cutters arranged upon the peripheral faces of the said body and being of substantially uniform width with the same, said knives or cutters having laterally 55 projecting ribs or portions extending beyond the side faces of the said central body portion of the cutter head and provided with outer faces arranged at an angle or inclination to the axis of the cutter head, and annular side plates adjustably secured to the body portion of the cutter head and provided with grooves having inclined outer 60 walls fitting the ribs or projecting portions of the knives or cutters, said grooves being 65 also provided with inner walls spaced from the ribs or projecting portions to enable the side plates to draw the knives or cutters inward radially of the cutter head to clamp 70 the knives or cutters tightly against the body portion of the cutter head, said cutter head being provided with outer side shallow recesses or grooves spacing the outer portions of the side plates from the central body portion. 75

In testimony whereof I affix my signature in presence of two witnesses.

ALEX J. JOHNSON.
